UNITED STATES PATENT OFFICE

WILLIAM A. CARMICHAEL, OF HAMDEN, AND FRANKLIN H. HART, OF NEW HAVEN, CONNECTICUT, ASSIGNORS TO C. COWLES AND COMPANY, OF NEW HAVEN, CONNECTICUT, A CORPORATION OF CONNECTICUT

SNAP-IN LOCK

Application filed June 25, 1929. Serial No. 373,583.

This invention relates to a door latch or lock, and particularly the latch or lock for automobile doors although it is not limited thereto.

5 It has for an object to provide an improved latch and lock construction which does not require the setting of any screws in assembling the handle in the door so as to reduce the cost of installation, to do away with 10 screws in the escutcheon in the outside of the door, and to prevent removal of the handle to permit operation of the latch by detachment of the escutcheon.

15 It is also an object of the invention to provide a latch or lock construction in which the handle and latch operating spindle may be assembled in the door by merely pushing it into position to thus reduce the cost of installation.

20 It is another object of the invention to provide a construction in which the handle can be removed only when the door is in the open position, and therefore, when the door is locked it is impossible to remove the handle 25 to gain access to the latch or locking means.

With the foregoing and other objects in view, the invention consists in certain novel features of construction, combinations and 30 arrangements of parts as will be more fully disclosed in connection with the accompanying drawings.

In these drawings,

Fig. 1 is a transverse section through a portion of an automobile door, its adjacent jamb and our improved lock construction, the section being substantially on line 1—1 of Fig. 2.

Fig. 2 is an inner view of the latch removed from the door, the plane of the view being substantially on line 2—2 of Fig. 1.

Fig. 3 is a detail section substantially on line 3—3 of Fig. 2.

Fig. 4 is a section similar to Fig. 1 of a portion of the door and latch only showing 45 how the device is used with a latch without locking it.

Fig. 5 is an enlarged detail section of the latch operating means showing how the securing means for the spindle may be released 50 to permit removal of the handle.

Fig. 6 is a transverse section substantially on line 6—6 of Fig. 1 but on a larger scale.

Fig. 7 is an end view of the latch operating bushing or follower.

Fig. 8 is a side elevation thereof partly 55 broken away.

Fig. 9 is an end view looking toward the bottom of Fig. 8.

Fig. 10 is a section substantially on line 60 10—10 of Fig. 4, and

Fig. 11 is a detail section substantially on line 11—11 of Fig. 2.

A common construction of latch and lock 65 for automobile doors has an escutcheon about the shank of the handle which is secured to the outer surface of the door by means of screws. This construction has numerous objections in that the appearance of the screws is objectionable as marring the appearance of the present style of body, and in assembling 70 there is often considerable difficulty in lining up the holes in the escutcheon, door and latch. Also, in installing these handles on the job there is often a tendency for the screw driver to slip and mar the paint on the door. Still 75 further the application of the screws requires a certain number of manual operations which in quantity production are quite expensive. Another objection to this type of construction is, that often an unauthorized 80 person can take out the screws of the escutcheon and remove the handle so as to gain access to the latch for retracting it to open the door.

We have overcome these difficulties and objections with a very simple construction 85 which requires no screws in assembling and which may be applied to the door by merely forcing it to position therein. We have done this by a very simple mechanism as will be 90 apparent from the accompanying drawings. The upright edge member of the frame of an automobile door is indicated at 12 with the outer sheet metal covering indicated at 13. The jamb of the door 14 has the usual metal 95 keeper 15 cooperating with the nose 16 of the latch bolt 17 which is guided for reciprocating movements as in the usual construction. In the present construction it is guided by a headed rivet 18 sliding in a slot 19 in the 100

rear wall 20 of the latch casing and also in an opening 21 in the portion 22 of the casing bent around on the edge of the door. It is also guided between the ears 23 on the front wall, and a spring 24 reacting against the shoulder 25 of the laterally extending arm 26 of the latch tends to shift the latch to the left as viewed in Figs. 1 and 2 to the holding position.

10 Mounted to turn in the wall 20 and a substantially U-shaped strap 27 secured to the rear surface of this wall, is a follower or bushing 28 which has a noncircular opening 29 therethrough to receive the similarly shaped 15 latch operating spindle 30. Usually the spindle 30 is a piece of square bar and is fastened to the shank 31 of the handle 32 on the outside of the door. The follower 28 carries a cam 33 which has an arm 34 engaging the free end 20 of the arm 26 on the latch bolt, the cam being provided with a noncircular opening to receive the noncircular portion 35 of the follower so as to turn therewith. Between the cam and flange 36 on the follower is a washer 37 holding one end 38 of a spring mounted on a stud 39 on the arm 34. The other arm 40 of this spring engages a catch 41 mounted on the opposite side of the flange 36 and mounted for limited lateral movement on 30 the follower 28. That is, the follower is provided with parallel surfaces 42 on the opposite sides thereof on which the catch slides, the width of the opening 43 in this catch being sufficient to permit the movement desired. One side wall of this opening is provided with a tongue 44 to project across a portion of the opening 29 in the follower and engage in a notch 45 in one side of the latch 40 operating spindle 30 to hold this spindle against longitudinal movement in the follower and secure the spindle and handle in proper position in the door.

Mounted on the spindle and shank 31 is a sleeve or collar 46 and it is mounted to slide longitudinally thereon. On one or both sides, preferably on diametrically opposite sides, this sleeve is slotted and the walls or slots forced outwardly to form longitudinal flanges 47 on opposite sides of the slots. The inner end of the sleeve is closed as shown at 48 while its outer end is turned laterally and inwardly as shown at 49 to form a flange or collar about the shank on the outside of the door. The metal covering of the shank 31 of 50 the handle extends inwardly over the end of the shank to form a shoulder 50 and mounted on the spindle between this shoulder and the end 48 of the sleeve is a washer having lateral projections 51 extending into the slots formed by the flanges 47. Between this washer and the end 48 is a compression spring 52 while a second washer 53 is mounted on the spindle inwardly of the end 48 and is held against inward movement by the lugs 54 struck up from the spindle. It will be apparent from this

construction that the spring 52 pressing against the washer 51 at its shoulder 50 tends to force the handle and spindle outwardly, while pressure of this spring at its other end against the closed end 48 of the sleeve 46 tends to force this sleeve inwardly and press the edge of the collar 49 against the outer surface 13 of the door.

In applying the handle 32 and the spindle 30 it will, of course, be understood the hole 75 or passage 55 is bored in the member 12 in alignment with the follower 28 and is counterbored at its outer end as shown at 56, and a similar opening 57 is provided in the metal plate 13. At opposite sides of this opening 57, however, are provided notches 58 to receive the flanges 47 of the sleeve 46 (see particularly Fig. 6) and prevent this sleeve 46 turning in the door while at the same time permitting the sleeve to have movements at 80 right angles to the door. The latch bar 17 with the follower and associated mechanism is assembled on the plate 20 without the spindle 30 and is applied as so assembled to the door. In applying the handle 32 of the spindle 30 all that is necessary is to insert the spindle 30 into the follower 28 until the tongue 44 of the latch 41 seats in the notch 45 in the spindle. The end of the spindle is inclined as shown at 59 so that as the 85 spindle is inserted in the follower, this inclined wall reacts against the tongue 44 to retract the catch as this tongue 44 projects through this notch 28' in the follower 28 and into alignment with the noncircular opening 29. As the spindle is inserted the flanges 47 of the collar 46 seat in the notches 58 in the sheet metal front wall 13 and prevent this collar turning in the door. The lengths of the elements are so proportioned that when 90 the spindle is in position, as shown in Figs. 1 and 4, the free edge of the collar 49 engages the front surface of the plate 13 and forces the collar outwardly somewhat to compress the spring 52 as shown in these figures. The spring 52, therefore, tends to 95 force the spindle outwardly against the action of the catch 41 and also presses the free edge of the collar 49 against the outer surface of the door, and therefore, prevents 100 looseness and rattling of the parts in the door and compensates for variations in the thickness of the doors incident to manufacture, so that in spite of these variations the handle is properly positioned in the door. 105 It will be obvious that the simple act of forcing the spindle into the door automatically fastens the spindle and handle in position, and therefore, no other assembling operations are required. Therefore, there 110 are no screws to be applied to the outside of the door, doing away with the expense of applying these screws, the objectionable appearance of these screws and the danger of marring the finish in applying them. It 115

120

125

130

will, of course, be understood that the central openings in the wall 48 and washer 51 through which the spindle 30 passes are sufficiently large to permit turning of the spindle in these elements. The wall 22 of the casing plate 20 is provided with an opening 60 opposite catch 41 so that a tool 61, such as the point of a screw driver, nail or other similar instrument, may be inserted to shift 5 the catch 41 laterally to the right as viewed in Figs. 1, 2, 4 and 5, and withdraw the tongue 44 from the notch 45 to permit withdrawal of the spindle 30 and the handle 32 as shown in Fig. 5. However, it will be 10 apparent that as the opening 60 is in the edge of the door it is inaccessible except when the door is open, and therefore, when the door is locked it is impossible for an unauthorized person to remove the handle 15 and spindle to thus gain access to the latch operating mechanism. It will, however, be apparent that the act of removing the handle and spindle is a very simple one and does not require the removal of any screws 20 or bolts. As the elements of the catch 41 and its spring 38-40 are mounted on the follower or bushing 28 they turn with it and are always in the same relation to each other. In the present construction the outward 25 movement of the latch bolt 17 under action of its spring 24 is limited by engagement of the arm 34 against the wall 22 as shown in Figs. 1 and 11.

In Fig. 4 the handle is shown without a 30 locking means while in Fig. 1 is shown how a locking means may be applied to this handle, it being the usual practice to apply both types to a car. That is, in four door cars, three doors would have the handle without 35 the lock, the latch being locked by separate locking means accessible from the interior of the car, while the fourth door is provided with a handle which has to be locked from the outside, such as the handle shown in 40 Fig. 1. The construction of the latch and the remainder of the handle are the same whether used with or without a lock and the handle is applied in the same way by merely forcing it into position with the end of the spindle in 45 the follower 28 where it is held by the catch 41. Mounted in the shank 31 of the handle is a lock cylinder 62 which is rotatable in the handle. It carries an eccentric pin 63 projecting into a transverse slot in a locking 50 bolt 64. This bolt is mounted to reciprocate in the transverse passage 65 in the shank by turning the cylinder 62 under action of the key 66. The bolt 64 is reciprocated by the pin 63 to move the free end of the bolt to or 55 from the slots formed by the flanges 47. Thus when the bolt is in the position of Figs. 1 and 6 with its outer end between one set of flanges 47 the bolt locks the handle against 60 turning because the sleeve 46 is held against 65 turning by coaction of the flanges 47 with

the sides of the notches 58. The cylinder 62 may be held in position by the transverse pin 67 in a peripheral groove in the cylinder. The cylinder lock 62 may be of any standard type controlled by pins or tumblers 68. 70

The member shown at 69 is connected to the latch bolt by a lost motion connection involving the pins 70 and 71 and slots 72 and 73, and is connected by a link 74 to any suitable means (not shown) accessible at the inner side 75 of the door for manipulating the latch from the interior of the car.

It will be obvious from the foregoing description that the lock is of very simple construction and may be assembled in the door with a minimum of labor, and thus assembly cost is greatly reduced over the old types and we have done away entirely with the screws at the outer surface of the door. Also that the construction automatically adapts itself 80 to the usual variations in the thickness of the doors incident to manufacture. 85

Having thus set forth the nature of our invention, what we claim is:

1. In a door latch, a movable latch bolt, a handle having a non-circular latch operating spindle, a bushing having a non-circular opening to receive said spindle and having spaced guiding surfaces, means operated by the bushing for shifting the latch bolt, a shoulder carried by the spindle, a catch carried by the bushing and having an opening therethrough with opposite sides of the opening guided for sliding movement by said surfaces, and a spring for yieldingly holding the catch in cooperation with said shoulder to prevent removal of the spindle from the bushing. 90

2. In a door latch, a movable latch bolt, a handle having a non-circular latch operating spindle, a bushing having a non-circular opening to receive said spindle and having spaced guiding surfaces on opposite sides thereof, means operated by the bushing for shifting the latch bolt, a shoulder carried by the spindle, a catch comprising a member having an opening to receive the bushing and guided by the edges of this opening on the guide surfaces for lateral sliding movement, 105 and a spring tending to shift the catch to a position in front of the shoulder to retain the spindle in the bushing. 110

3. In a door latch, a movable latch bolt, a handle having a non-circular latch operating spindle, a bushing having an non-circular opening to receive said spindle and having spaced guiding surfaces, means operated by the bushing for shifting the latch bolt, a shoulder carried by the spindle, a movable catch carried by said bushing and provided with an opening to receive said bushing and guided by edges of said opening on said surfaces for lateral sliding movement, a spring 120 tending to hold the catch in front of the 125

shoulder to retain the spindle in the bushing, and the end of the spindle being inclined to engage the catch and retract it against the action of the spring as the spindle is inserted in the bushing.

In testimony whereof we affix our signatures.

WILLIAM A. CARMICHAEL.
FRANKLIN H. HART.
